MACHINE FOR OPERATING ON
SHOE UPPERS

Bernhardt Jorgensen, Marblehead, Mass., assignor
to United Shoe Machinery Corporation, Paterson, N. J., a corporation of New Jersey

Application November 21, 1935, Serial No. 50,887

33 Claims. (Cl. 12—9)

This invention relates to machines for operating on shoe uppers, and is herein illustrated as applied to a machine for lasting the toe ends of shoes. In the manufacture of shoes of that 5 type in which the margin of the upper is lasted over an insole in generally parallel relation to the bottom of the last, if an adhesive is used to secure the upper to the insole, it is customary to remove at the toe end by a trimming operation the surplus margin of some of the layers 10 of the upper materials, usually of the toe box and the lining, so that the margin of the outer layer of the materials will lie, at least for the most part, next to the insole. It is an object of 15 the present invention to provide means for quickly and accurately performing such a trimming operation. The invention is herein illustrated as applied to an automatic lasting machine of the same general character as disclosed in United 20 States Letters Patent No. 1,980,435, granted on November 13, 1934 upon an application of C. F. Pym and A. F. Pym, but so modified as to dispense with the use of upper-fastening tacks. It is to be understood, however, that in various 25 novel aspects the invention is not limited to an organization of that character.

With the above and other objects in view, the machine herein shown is provided with a cutter 30 movable lengthwise of the last to trim the margin of all but the outer layer of the upper materials around the toe end of the last, combined with upper-pulling means which conforms the upper materials to the contour of the toe end of the last and positions them in proper relation 35 to the cutter and to the edge of an insole on the last for the trimming operation. More particularly, as herein illustrated, the upper-pulling means comprises a toe gripper of novel construction which clamps the marginal portions of the 40 several layers of the upper materials outspread around the toe end of the last with the marginal portion of the outer layer separate from the other layers, and supported on this toe gripper is a spring-operated cutter which is automatically 45 released to render it operative at an adjustably predetermined time in the upper-pulling movement of the gripper so that the cut will be made in the desired relation to the edge of the insole. Preferably the time of operation of the cutter 50 is so determined that only about an eighth of an inch, for example, of the toe box and the lining will overlap the bottom face of the insole after the lasting operation. As further herein illustrated, the toe gripper continues its movement after the operation of the cutter, with a

further pulling effect on the outer layer of the upper materials the margin of which, however, slips partially out of the gripper jaws, and after the pull the margin of the outer layer is wiped inwardly over the insole by lasting wipers. 5

The novel features of the invention, including various novel details of construction and combinations of parts, will now be more particularly described by reference to the accompanying drawings and thereafter pointed out in the claims. 10

In the drawings,

Fig. 1 is a view partly in side elevation and partly in section of a portion of a machine organization of the character disclosed in the above-mentioned Letters Patent with features of the 15 present invention embodied therein;

Fig. 2 shows the top of the forepart of a shoe and the toe and side grippers of the machine as viewed in the direction of the arrow A in Fig. 1, with the grippers gripping the margin of the upper materials; 20

Fig. 3 shows a portion of the mechanism for operating the toe gripper as viewed in the direction of the arrow B in Fig. 1, with parts broken away;

Fig. 4 is a view of the toe gripper and the trimming mechanism as viewed in the direction of the arrow C in Fig. 1, with parts broken away;

Fig. 5 is a section on the line V—V of Fig. 4;

Fig. 6 is a perspective view of a portion of the 30 trimming mechanism; and

Figs. 7, 8, 9, and 10 are views illustrating the positions of various parts at different times in the operation of the machine.

Since the novel features of the invention are, 35 as previously stated, herein illustrated as embodied in a machine organization such as fully shown and described in the above-mentioned Letters Patent, only such parts of the machine as it is necessary to refer to for an understanding of 40 the invention are shown in the drawings and will be hereinafter described. The assembled shoe and last are positioned and supported in the correct relation to the operating instrumentalities by three pins 2 arranged to extend through holes in 45 the insole into sockets provided in the last, these pins being fast on a plate 4 secured to a member 6 which is adjustable in directions lengthwise of the shoe by means of a hand wheel 8. While the shoe is thus correctly positioned without the necessity for any care on the operator's part, it is to 50 be understood that the invention is not dependent upon the use of work-positioning means of this particular character. For pulling the upper over the last at each side of the forepart there 55

are provided two side grippers 10 and 12 arranged to grip and pull the upper respectively in a location substantially at the tip line, if the shoe is provided with a toe tip, and in a location substantially at the ball of the shoe. The construction of these grippers and of the mechanisms whereby they are operated to grip and to pull the upper may be the same as disclosed in the previously mentioned Letters Patent and therefore need not be described in detail, the upper-pulling movements being imparted to the two side grippers shown in Fig. 1 by a lever 14 a portion of which is shown in dotted lines and which corresponds to the lever 318 shown in said Letters Patent. For pulling the toe end of the upper the machine herein shown has a single gripper instead of the three grippers of the prior disclosure, and for purposes of the present invention this gripper is so constructed as to clamp the marginal portion of the outer layer of the upper materials outspread around the toe end of the last in a plane substantially parallel to the bottom of the forepart of the last and to clamp the marginal portions of the other layers of the upper materials, comprising, for example, the lining and the toe box, similarly outspread in a plane parallel to the clamped margin of the outer layer. For this purpose the toe gripper comprises an intermediate flat jaw 16 (Figs. 4 and 5), an upper jaw 18 arranged to cooperate with the upper face of the jaw 16 to clamp the margin of the outer layer of the upper materials, and a lower jaw 20 arranged to cooperate with the lower face of the jaw 16 to clamp the margins of the other layers of the materials. The intermediate jaw 16 is provided with two depending pins 22 slidably mounted in bearings in the lower jaw 20 and having lower end portions of reduced diameter slidably mounted in lugs 24 formed on a gripper casing 26, one of these lugs 24 being shown in Figs. 7, 8 and 9. The lower jaw 20 is formed as part of a slide 28 mounted for rectilinear upward and downward movements in the casing 26. The upper jaw 18 has a depending shank portion 30 pivotally mounted on a pin 32 on the upper end of the casing 26 and provided with a roll 34 normally in engagement with a face 36 on the slide 28 with the jaw 18 in open position, the jaw being held normally in this position by a spring 38 coiled about the pin 32. The slide 28 is further provided with a cam face 40 which, by engagement with the roll 34, swings the jaw 18 into position to clamp the outer layer of the upper materials against the jaw 16 in response to upward movement of the slide 28. As the slide is thus moved upwardly it also carries the jaw 20 into position to clamp the other layers of the upper materials against the intermediate jaw 16. When the jaws are in open positions the portions of the pins 22 which are of larger diameter rest at their lower ends on the lugs 24, as shown in Fig. 1, and in the closing of the jaws the intermediate jaw 16 is carried more or less upwardly in a straight path toward the swinging jaw 18 by the action of the jaw 20 in pressing the upper materials against the jaw 16, as will be evident from the relation of the pins 22 to the lugs 24 in Fig. 7. It will thus be seen that the pressures of the jaws on the several layers of the upper materials are substantially equalized. When the jaws are in gripping or clamping positions the roll 34 is engaged by another face 42 formed on the slide 28 in parallel relation to the face 36, as illustrated in Fig. 7. All the jaws preferably have smooth upper-clamping faces, as shown, and during the pull the upper materials may slip more or less

between the jaws so as to be partially withdrawn from the jaws.

The mechanism for operating the slide 28 to close the jaws on the upper materials, while embodying features disclosed in the above-mentioned Letters Patent, is actually constructed in accordance with the somewhat different disclosure of Letters Patent No. 2,039,448, granted on May 5, 1936 upon an application of Arthur F. Pym. For imparting upward movement to the slide 28 to close the jaws there is provided in the casing 26 another slide 44 which is held from turning in the casing by a key 46. Between this slide and the slide 28 is a spring 48 which bears at its upper end on a washer 50 in engagement with a shoulder formed on a sleeve 52 which is threaded on the reduced lower end of the slide 28. Extending upwardly from the slide 44 through the spring 48 and into a recess in the lower end of the slide 28 is a stem 54 which carries a pin 56 extending into a slot 58 in the lower end of the slide 28. This pin serves to transmit downward movement to the slide 28 from the slide 44 in the opening of the gripper jaws. The pin 56 and the slot 58 are so arranged that the spring 48 is maintained initially under some compression.

Upward movement is imparted to the slide 44 to close the jaws yieldingly through the spring 48 by a member 60 which for that purpose is rotatable in the casing 26 about an axis extending lengthwise of the gripper, the upper end of this member being formed to provide a spiral track 62 in engagement with a complementary formed spiral track on the lower end of the slide 44. It will be understood that these spiral tracks act as cooperating cam faces whereby the slide 44 is forced upwardly by turning movement of the member 60 in one direction. To assist in imparting downward movement to the slide 44 when the member 60 is turned in the opposite direction, there is secured in a recess in this member a stem 64 which extends upwardly into a recess in the slide 44, this stem having therein a spiral groove 66 parallel to the spiral track 62. Extending into this groove is a pin 68 carried by the slide 44. It will be understood that the groove 66 and the pin 68 cooperate with the spiral tracks in forcing the slide 44 upwardly to close the jaws and are effective to impart downward movement to the slide 44 in the opening of the jaws.

The member 60 has a diametrically enlarged portion 70 which lies in an enlarged bore in the casing 26 to hold the member against upward movement relatively to the casing, and below this enlarged portion is a washer 72 seated against the lower end of the casing 26 and confined by a cap 74 threaded on the lower end of the casing. This cap serves also to confine a roller bearing 76 for the member 60 and for a stem 78 extending downwardly from this member. The stem 78 is connected by a universal joint 80 to a shaft 82 which is rotatable to close and open the gripper jaws. The shaft 82 extends downwardly through a bearing in the frame which is of greater diameter than the shaft and carries two sleeve members 84 of the same diameter as the bearing to assist in guiding the shaft in its turning movements and in lengthwise movements thereof to operate the gripper. Between the two sleeve members 84 there is formed on the shaft 82 an elongated pinion 86 engaged by a pinion 88 whereby the shaft is turned to close and open the gripper jaws. The mechanism for operating the pinion 75

88 is not herein shown in detail, since it is the same as disclosed in the previously mentioned Letters Patent No. 1,980,435. Lengthwise downward movement of the shaft 82 for operating the gripper to pull the upper is effected by a forked lever 90 operated also by mechanism of the same character as disclosed in the last-mentioned Letters Patent, this lever being connected by a two-armed link 92 (Fig. 3) to pins 94 mounted in a bar 96 which, through ball bearings 98, is connected to the lower end of the shaft 82 and one of the sleeves 84 on the shaft. In imparting downward upper-pulling movement to the shaft 82 the bar 96 acts through one of the ball bearings on a collar 100 fast on the lower end of the shaft, and in imparting reverse upward movement to the shaft the bar acts through the other ball bearing on the lower end of the sleeve 84.

20 The toe gripper is guided in its downward and upward movements by two plates 102 engaging opposite sides of the gripper casing 26 and having flanges which extend into grooves 104 in the casing, substantially as disclosed in the previously mentioned Letters Patent No. 1,980,435. These two plates are pivotally connected by studs 106, Fig. 4) to the two arms of a forked member 108 having a cylindrical shank portion 110 (Fig. 1) slidably mounted in a bearing in the frame to permit swinging movements of the toe gripper in directions lengthwise of the last. A spring 112 connected to the member 108 tends to move the member in one direction and holds it normally in a position adjustably determined 35 by a screw 114 which is threaded in the frame and has a conically shaped end engaging the outer end of the shank portion 110 of the member 108.

Extending downwardly from the lower toe gripper jaw 20 are two rods 116 which are secured to the jaw at their upper ends. At their lower ends the rods 116 are slidably mounted in thimbles 118 which are threaded in a bracket 120 fast on the gripper casing 26. The two rods 116 serve as guides for a block 122 on the upper face of which is secured by a bolt 124 and dowel pins 126 a trimming cutter 128. The upper edge of this cutter is in a plane parallel to the plane of the lower face of the intermediate gripper jaw 16 which is provided with a brass insert 130 opposite the edge of the cutter to cooperate with the latter in trimming the margin of the layers of the upper materials clamped between the jaws 16 and 20. The cutter 128 is so shaped that its edge is curved in substantially parallel relation to the curvature of the edge of the insole around the end of the toe and is flared outwardly at the sides of the toe so as to sever completely from the remainder 50 of the upper materials the surplus margin of the layers on which the cutter operates. The operation of the cutter occurs at a predetermined time in the upper-pulling movement of the toe gripper after a substantial pull has been applied to all the layers of the upper materials, but prior to the completion of the upper-pulling movement, through the operation of mechanism which will now be described.

Upper-trimming movement is imparted to the cutter 128 by two springs 132 mounted on the rods 116 and held under compression between the block 122 and the thimbles 118, these thimbles being adjustable to vary the amount of compression of the springs. Normally the block 122 and the cutter 128 are held in a depressed position,

as shown in Figs. 4 and 5, by a latch 134 in engagement with a hook member 136 secured to the block 122. The latch 134 is pivotally mounted at its lower end on a pin 138 supported in two upwardly extending ears of the bracket 120 which is secured as above described to the gripper casing 26. A leaf spring 140 fast on the bracket 120 holds the latch yieldingly in operative position. Also mounted to swing on the pin 138 is an arm 142 (Fig. 6) provided with an ear 144 in which is loosely swiveled a spindle 146, a portion of the spindle being threaded in the latch 34. The spindle 146 is held against lengthwise movement relatively to the ear 144 by a flange 148 formed on the spindle at one side of the ear and by a knurled head 150 at the other side of the ear. At its upper end the arm 142 carries a roll 152 which at a predetermined time in the upper-pulling movement of the gripper is engaged by a cam face 154 formed on one of the gripper-guiding plates 102. By the action of this cam face on the roll the arm 142 and the latch 134 connected thereto are swung to disconnect the latch from the hook member 136, thus releasing the cutter 128 to 25 the action of the springs 132 which force it upwardly and trim the upper materials in the manner hereinbefore described. By turning the spindle 146 the arm 142 may be swung relatively to the latch 134 in such manner as to vary the 30 time in the upper-pulling movement of the gripper when the cam face 154 becomes effective to release the cutter. This serves to vary the relation of the cut to the edge of the insole so as to determine how far, if at all, the trimmed layers will overlap the bottom of the insole. The cutter is returned into position to be held by the latch 134 in response to upward movement of the toe gripper to starting position after the operations on the shoe have been completed. For 40 this purpose the two gripper-guiding plates 102 carry a rod 156 arranged to engage the angularly shaped lower end of a slide 158 which is mounted in contiguous relation to the gripper casing 26 and is connected at its upper end to 45 the block 122, as illustrated in Fig. 5. It will be understood that at a predetermined time in the upward movement of the gripper the lower end of the slide 158 engages the rod 156 and the slide and the block 122 are then held stationary by the rod as the gripper continues its upward movement and carries the latch 134 into 50 position to connect with the hook member 136. In the operative movement of the gripper the slide 158 moves with it so that the angularly shaped lower end of the slide is carried away 55 from the rod 156 to permit the operative movement of the cutter when the latter is released by the latch 134.

After the operation of the cutter 128 as above 60 described, the toe gripper continues its downward movement to carry its jaws below the plane of the forepart of the shoe bottom, and in such continued movement it imparts a further pull to the outer layer of the upper materials, the margin of which, however, may slip more or less between the smooth faces of the jaws which grip it. Thereafter the upper is operated upon by a toe band 160 (Fig. 9) and by wipers 162 (Fig. 10) in substantially the same manner as disclosed in Letters Patent No. 1,980,435. That is, the toe band embraces the upper around the toe and by downward movement wipes it toward the edge of the insole, after which the wipers 162 are advanced and closed to wipe the 75

margin of the outer layer of the upper materials and as much of the other layers as may project beyond the edge of the insole around the toe inwardly over the insole, as illustrated in Fig. 10. The wipers 162 may, as shown, be of sufficient lengths to wipe the upper materials inwardly over the insole also along the sides of the forepart as far rearwardly as the ball of the shoe. The mechanisms for operating the toe band 160 and the wipers 162 are not shown herein, in view of the complete disclosure of such mechanisms in the last-mentioned Letters Patent. The shoe is supported against upward pressure of the wipers thereon by a holder 164 (Fig. 10) controlled and operated also as disclosed in said Letters Patent. Since the upper materials are fastened to the insole by adhesive, the tack-driving mechanism and the tack-supplying mechanism of the prior machine are omitted. Corresponding, however, substantially in location to the tack block of that machine is a block 166 having a depending stem detachably connected by a screw 167 to a rod 168 (Fig. 1) movable upwardly and downwardly in a guideway in the frame, the block 166 having opposite side portions arranged to extend upwardly at the sides of the shoe support member 6 for engagement with the margin of the insole along the sides of the forepart to insure that the margin of the insole will be positioned close to the bottom of the last prior to the inward movements of the wipers 162. The lower end of the rod 168 is connected by a link 170 to a lever 172 which is operated in the same manner as the corresponding lever 802 for controlling the tack block in the machine disclosed in Letters Patent No. 1,980,435. The block 166 is pressed upwardly against the insole after the upper-pulling operation, as shown in Fig. 9, and is then moved downwardly away from the insole to provide room for the wipers 162. After these wipers have wiped the margin of the upper inwardly over the insole the block 166 is again moved upwardly and by engagement with these wipers (Fig. 10) assists in pressing them more forcibly against the shoe bottom, similarly to the disclosure of said Letters Patent.

It will be understood that before a shoe is presented to the machine a suitable adhesive will have been applied thereto for securing the forepart of the upper to the insole. Such adhesive may be applied, for example, to the margin of the insole and to the different layers of the upper materials, except that preferably no adhesive will be applied around the toe end to the marginal portion of the lining and the toe box to be severed by the cutter 128. In presenting the shoe to the machine, after mounting it on the pins 2, the operator arranges the margin of the upper materials in proper relation to the jaws of the toe gripper, with the margin of the outer layer of the materials outspread upon the top of the intermediate jaw 16 and the margin of the other layers between the jaws 16 and 20. If the machine is equipped with means such as disclosed in Letters Patent No. 1,980,435 for closing the toe gripper on the upper prior to the starting of the power operation of the machine, the operator may then cause the toe gripper jaws to close and grip the different layers of the upper materials before arranging the margin of the materials in proper relation to the jaws of the side grippers 10 and 12 and then starting the machine. Alternatively, or if the machine is not

equipped with means of that character for controlling the toe gripper, the operator will arrange the upper materials in proper relation to all the gripper jaws, which will close automatically upon the starting of the machine. After the starting of the machine the upper is pulled by all the grippers, and the machine then comes to a stop with the grippers holding the upper under tension to permit any adjustments which may be necessary. At a predetermined time in the upper-pulling movement of the toe gripper, depending upon the adjustment of the cam roll 152 relatively to the cam face 154, the cutter 128 is released by the latch 134 and is impelled upwardly by the springs 132 to sever the surplus margin of the layers of upper materials pulled by the cooperating jaws 16 and 20. This trimming operation will take place, for example, when the parts are positioned as shown in Fig. 8. Thereafter the toe gripper continues its downward movement to make room for the toe band 160 and the wipers 162 in their operation on the shoe, and thus applies a further pull to the outer layer of the upper materials, which will slip more or less between the gripping jaws 16 and 18, as illustrated in Fig. 9. Before starting the machine the second time the operator moves the shoe holder 164 into engagement with the shoe, as fully disclosed in Letters Patent No. 1,980,435, and upon the starting of the machine this shoe holder is pressed down more firmly against the shoe. The toe band 160 is then applied in clamping relation to the upper materials around the toe (Fig. 9) and is moved downwardly to wipe the materials toward the edge of the insole. At approximately the same time the block 166 is moved up to press the margin of the insole against the last along the sides of the forepart, as also illustrated in Fig. 9. The wipers 162 are thereafter advanced and closed to wipe the marginal portion of the upper materials inwardly over the insole. As these wipers begin their wiping movements the several grippers are opened to release the upper and the block 166 is lowered to make way for the wipers. Substantially at 45 the ends of the advancing and closing movements of the wipers 162 they are pressed more forcibly upward against the shoe bottom by the spring means disclosed in Letters Patent No. 1,980,435, and their pressure on the overwiped margin of 50 the upper materials is further increased by moving the block 166 up against their lower faces (Fig. 10). The marginal portion of the upper materials is thus pressed firmly into adhering relation to the insole. Thereafter the parts of the machine are returned to their starting positions and the operator removes the shoe from the pins 2. When the toe gripper jaws open the marginal upper materials severed by the cutter 128 are released and may be removed by the operator 60 from between the jaws 16 and 20.

While the trimming means is herein shown as applied to a machine which lasts the toe end of the shoe, it is to be understood that advantages with respect, for example, to the accuracy of the trimming, by reason of the conforming or shaping of the upper materials to the toe end of the last preparatory to the operation of the cutter, are not necessarily confined to a machine of that character.

Having described the invention, what I claim as new and desire to secure by Letters Patent of the United States is:

1. In a machine for operating on shoe uppers, means for conforming a plurality of layers of

upper materials to the toe end of a last, and upper-trimming mechanism comprising a cutter arranged relatively to said conforming means to sever from the upper materials, by a cut directed heightwise of the last and continuous all around the end of the toe, the surplus margin of less than the total number of layers of the materials.

2. In a machine for operating on shoe uppers, means for conforming to the toe end of a last a plurality of layers of upper materials including a toe box and a lining located between the last and an outer layer of the materials, and upper-trimming mechanism comprising a cutter arranged relatively to said conforming means to sever from the upper materials, by a cut directed heightwise of the last and continuous all around the end of the toe, the surplus margin of the toe box and the lining while leaving the outer layer of the materials intact.

20 3. In a machine for operating on shoe uppers, means for conforming a plurality of layers of upper materials to the toe end of a last, upper-trimming mechanism comprising a cutter arranged relatively to said conforming means to trim, by a cut directed heightwise of the last and extending around the end of the toe, the margins of all the layers of the upper materials except the outer layer while the several layers are held in conformity to the last, and means for laying the margin of the toe end of the outer layer of the materials inwardly over an insole on the last after the trimming operation.

4. In a power-operated machine for operating on shoe uppers, power-operated means for conforming a plurality of layers of upper materials to the toe end of a last, and upper-trimming mechanism movable in automatically determined time relation to said conforming means to sever from the upper materials around the end of the toe the surplus margin of less than the total number of layers of the materials.

5. In a power-operated machine for operating on shoe uppers, power-operated means for conforming to the toe end of a last a plurality of layers of upper materials including a toe box and a lining located between the last and an outer layer of the materials, upper-trimming mechanism comprising a cutter movable in automatically determined time relation to said conforming means to sever from the upper materials around the end of the toe the surplus margin of the toe box and the lining, and means for laying the margin of the outer layer of the upper materials inwardly over an insole on the last after the trimming operation.

6. In a machine for operating on shoe uppers, means for conforming upper materials to the toe end of a last, a cutter for trimming the margin of said materials, spring means for operating said cutter, and mechanism for releasing said spring means to effect the operation of the cutter.

7. In a machine for operating on shoe uppers, means for conforming a plurality of layers of upper materials to the toe end of a last, a spring-impelled cutter movable to sever from the upper materials around the end of the toe the surplus margin of less than the total number of layers of the materials, and means for releasing said cutter to render it operative.

70 8. In a machine for operating on shoe uppers, means for conforming a plurality of layers of upper materials to the toe end of a last with their marginal portions outspread in substantially parallel relation to the bottom of the forepart of the last, and upper-trimming mechanism

comprising a cutter movable heightwise of the last to sever from the upper materials around the end of the toe the surplus outspread margin of less than the total number of layers of the materials.

9. In a machine for operating on shoe uppers, means for conforming a plurality of layers of upper materials to the toe end of a last with their marginal portions outspread in substantially parallel relation to the bottom of the forepart of the last, a cutter movable heightwise of the last to sever from the upper materials around the end of the toe the surplus outspread margin of less than the total number of layers of the materials, spring means for operating said cutter, and mechanism for releasing said spring means to effect the operation of the cutter.

10. In a machine for operating on shoe uppers, means for conforming to the toe end of a last a plurality of layers of upper materials including a toe box and a lining located between the last and an outer layer of the materials and for clamping the marginal portions of said layers outspread around the toe, upper-trimming mechanism comprising a cutter movable heightwise of the last to sever from the upper materials around the end of the toe the surplus outspread margin of the toe box and the lining while leaving the margin of the outer layer of the materials intact, and wiping means movable thereafter to wipe the margin of the outer layer of the upper materials inwardly over an insole on the last.

11. In a machine for operating on shoe uppers, members arranged to clamp the margin of upper materials between them around the toe end of a last exteriorly of the edge of the last bottom, and a cutter movable heightwise of the last to trim said clamped margin by a cut extending continuously all around the end of the toe.

12. In a machine for operating on shoe uppers, members arranged to clamp between them the margin of less than the total number of layers of upper materials at the toe end of a last and to position the clamped margin relatively to the edge of an insole on the last, and a cutter arranged to sever from the upper materials at a predetermined distance from the edge of the insole the surplus margin of the layer or layers thus clamped.

13. In a machine for operating on shoe uppers, members arranged to clamp between them the margin of a toe box and a lining separately from an outer layer of the upper materials at the toe end of a last, and a cutter movable to sever the surplus clamped margin of said toe box and lining from the remainder of the upper materials while leaving the outer layer of the materials intact.

14. In a machine for operating on shoe uppers, means for pulling over the toe end of a last a plurality of layers of upper materials including a toe box and a lining located between the last and an outer layer of the materials, and mechanism movable in automatically determined time relation to said upper-pulling means to trim the toe box and the lining while leaving the outer layer of the upper materials intact.

15. In a machine for operating on shoe uppers, means for pulling over the toe end of a last a plurality of layers of upper materials while separately clamping the marginal portions of different layers, and means for trimming the margin of one or more of said clamped layers while leav-

- ing the margin of a separately clamped layer intact.
16. In a machine for operating on shoe uppers, means for pulling over the toe end of a last a plurality of layers of upper materials while separately clamping the marginal portions of different layers outspread, and a cutter movable heightwise of the last to trim the margin of one or more of said layers while leaving the margin of 10 a separately clamped layer intact.
17. In a machine for operating on shoe uppers, a gripper movable to pull upper materials over a last, a spring-operated cutter carried by said gripper for trimming the margin of said upper materials, and means for rendering said cutter operative in response to the movement of the gripper.
18. In a machine for operating on shoe uppers, a gripper movable to pull a plurality of 20 layers of upper materials over the toe end of a last, a cutter movable to trim the margin of less than the total number of layers of the upper materials, and means for rendering said cutter operative in response to the movement of the 25 gripper.
19. In a machine for operating on shoe uppers, a gripper movable to pull a plurality of layers of upper materials over the toe end of a last, a cutter movable to trim the margin of less than 30 the total number of layers of the upper materials, spring means for operating said cutter, and means controlled by the gripper for releasing said spring means to effect the operation of the cutter.
- 35 20. In a machine for operating on shoe uppers, a gripper movable to pull a plurality of layers of upper materials over the toe end of a last, a cutter carried by said gripper for trimming the margin of less than the total number of layers of the 40 upper materials, spring means for operating said cutter, a latch for holding the cutter normally retracted against the resistance of said spring means, and cam means arranged to act on said latch to release the cutter in response to the 45 movement of the gripper.
21. In a machine for operating on shoe uppers, a gripper for pulling a plurality of layers of upper materials at the toe end of a last heightwise of the last adjacent to the edge of an insole on the 50 last, upper-trimming mechanism arranged to sever from the upper materials pulled by said gripper the surplus margin of one or more of said layers by a cut in predetermined relation to the edge of the insole while leaving the outer 55 layer intact, and means for varying the relation of said cut to the edge of the insole.
22. In a machine for operating on shoe uppers, a gripper movable to pull a plurality of layers of upper materials at the toe end of a last heightwise of the last, a cutter carried by said gripper and arranged to sever from the upper materials the surplus margin of one or more of said layers while leaving the outer layer intact, means for 60 operating said cutter in predetermined time relation to the movement of the gripper prior to the completion of that movement, and means for varying the time in the movement of the gripper when the cutter is thus operated.
23. In a machine for operating on shoe uppers, 70 a gripper for pulling a plurality of layers of upper materials over the toe end of a last, said gripper having an intermediate jaw and other jaws for clamping different layers of the upper materials respectively against opposite faces of the intermediate jaw, and mechanism for trimming the 75 margin of the layer clamped against one of said faces while leaving intact the layer clamped against the other face.
24. In a machine for operating on shoe uppers, a gripper for pulling a plurality of layers of upper 5 materials over the toe end of a last, said gripper having an intermediate jaw and other jaws for clamping different layers of the upper materials respectively against opposite faces of the intermediate jaw, and a cutter having a cutting edge 10 arranged to act against one face of said intermediate jaw to trim the margin of the layer of upper materials clamped against that face while leaving intact the margin clamped against the other face of the intermediate jaw. 15
25. In a machine for operating on shoe uppers, a gripper for pulling over the toe end of a last a plurality of layers of upper materials including a toe box and a lining located between the last and an outer layer of the materials, said gripper 20 having an intermediate jaw, a second jaw for clamping the margin of the outer layer of the upper materials outspread upon one face of the intermediate jaw, and a third jaw for clamping the margin of the toe box and lining outspread 25 upon the other face of the intermediate jaw, and a cutter movable heightwise of the last to trim the margin of the toe box and lining while leaving the margin of the outer layer of the upper materials intact. 30
26. In a machine for operating on shoe uppers, a gripper movable to pull over the toe end of a last a plurality of layers of upper materials including a toe box and a lining located between the last and an outer layer of the materials, 35 said gripper having an intermediate jaw, a second jaw for clamping the margin of the outer layer of the upper materials outspread upon one face of the intermediate jaw, and a third jaw for clamping the margin of the toe box and lining outspread upon the other face of the intermediate jaw, a cutter movable to trim the margin of the toe box and lining, spring means for operating said cutter, and mechanism for releasing the cutter to the action of said spring 40 means in response to the upper-pulling movement of the gripper. 45
27. In a machine for operating on shoe uppers, a gripper movable to pull over the toe end of a last a plurality of layers of upper materials 50 including a toe box and a lining located between the last and an outer layer of the materials, a cutter movable to trim the margin of the toe box and the lining at a predetermined time in the upper-pulling movement of the gripper prior 55 to the completion of that movement, and means for wiping the margin of the outer layer of the upper materials inwardly over an insole on the last after the pull.
28. In a machine for operating on shoe uppers, a gripper movable to pull a plurality of layers of upper materials over the toe end of a last, mechanism automatically operative at a predetermined time in the upper-pulling movement of the gripper to sever from the upper 60 materials around the end of the toe the surplus margin of one or more of the layers of the materials while leaving the margin of the outer layer intact, the gripper being thereafter further movable to pull the outer layer while permitting 70 it to slip in the gripper jaws, and means for wiping the margin of the outer layer inwardly over an insole on the last after the pull. 75
29. In a machine for operating on shoe uppers, a gripper for pulling a plurality of layers 75

of upper materials over the toe end of a last, said gripper having jaws for clamping the margins of the several layers of the upper materials outspread with the margin of the outer layer separate from the margins of the other layers, and mechanism automatically operative at a predetermined time in the upper-pulling operation to sever from the upper materials around the end of the toe the surplus margins of said other layers while leaving the margin of the outer layer intact.

30. In a machine for operating on shoe uppers, a gripper for pulling a plurality of layers of upper materials over the toe end of a last, said gripper having an intermediate jaw and other jaws for clamping different layers of the upper materials respectively against opposite sides of the intermediate jaw with the margins of the different layers around the toe outspread in substantially parallel relation to the bottom of the forepart of the last.

31. In a machine for operating on shoe uppers, a gripper for pulling a plurality of layers of upper materials over a last, said gripper having an intermediate jaw and other jaws for clamping different layers of the upper materials respectively against opposite sides of the intermediate jaw, said other jaws being mounted re-

spectively for rectilinear movement and for swinging movement toward the intermediate jaw.

32. In a machine for operating on shoe uppers, a gripper for pulling a plurality of layers of upper materials over a last, said gripper having an intermediate jaw, a second jaw rectilinearly movable toward said intermediate jaw to clamp a layer of the upper materials, and a third jaw mounted for swinging movement toward the intermediate jaw to clamp another layer of the materials in response to the rectilinear movement of said second jaw.

33. In a machine for operating on shoe uppers, a gripper for pulling a plurality of layers of upper materials over a last, said gripper having an intermediate jaw, a second jaw rectilinearly movable toward said intermediate jaw to clamp a layer of the upper materials, and a third jaw mounted for swinging movement toward the intermediate jaw to clamp another layer of the materials in response to the rectilinear movement of said second jaw, said intermediate jaw being rectilinearly movable in response to the movement of the second jaw for equalizing the pressures of the jaws on the different layers of the upper materials.

BERNHARDT JORGENSEN.
